UNITED STATES PATENT OFFICE.

WILLIAM M. SMITH, OF PHILADELPHIA, PENNSYLVANIA, ASSIGNOR, BY
MESNE ASSIGNMENT, TO C. E. L. HOLMES, OF NEW YORK, N. Y.

SEWING-MACHINE.

SPECIFICATION forming part of Letters Patent No. 235,579, dated December 14, 1880.

Application filed January 15, 1880.

To all whom it may concern:

Be it known that I, WILLIAM M. SMITH, of the city and county of Philadelphia, State of Pennsylvania, have invented an Improvement 5 in Sewing-Machines, of which the following is the specification.

My invention relates to machines for sewing, overseaming, and embroidering; and it consists of certain mechanism combined with the 10 overhanging stationary arm and reciprocating needle-bar of a sewing-machine, as fully described hereinafter, whereby the needle may be moved in different directions and the movements regulated to change the positions of 15 the stitches.

In the drawings forming part of this specification, Figure 1 is a perspective view of sufficient of a Singer sewing-machine to illustrate my invention. Figs. 2 and 3 are detached 20 views, showing the cam for operating the vibrating needle-carrier; Fig. 4, a plan, partly in section, of the said cam and adjacent parts; Fig. 5, a perspective view of the needle-carrier and attachments; Fig. 6, a perspective view, 25 showing the lower end of the needle-bar and attachment; Fig. 7, a perspective view of the guide-pin used with the cam; Fig. 8, a diagram illustrating the adjustment of the stitch.

A represents the head, and A' the stationary arm, of a sewing-machine; B, the main or driving shaft, operating to give a vertical reciprocation to the needle-bar C. These parts are similar to those in a Singer sewing-machine, in which the lower thread is carried by 30 a shuttle reciprocating in a fixed race. The needle c is not directly attached to the said bar C, but is secured by the screw e in the head e' of a lever, E, pivoted at e' to a bracket, C', fastened by a screw, c', to the end of the 35 needle-bar C. The latter is shown as cut away or recessed at c', and formed with a convex side or face, c', in said recess, which receives and bears against a corresponding concave face or side, e', on the head e' of said lever E, 40 thereby forming guides to give steadiness of movement to the lever E as it vibrates from side to side.

E' is a guide-post arising from the end of the lever E, as shown. Said guide-post enters and vertically reciprocates in the bifur-

cated end f of the lever F, which is pivoted at f' to the head of the machine, and is provided with a curved slot, f''. The bifurcated end f of said lever F also acts as a presser-arm to move said guide-post E' from side to side to 55 vibrate the needle-carrying lever E when the lever F is oscillated on its pivotal point.

G is a rod, made in two sections, G' G'', united by the screw-threads g formed on the ends of said sections. Said rod is connected at one end to the lever F by the thumb-screw g'', which passes through the curved slot f'' of lever F, and is provided with an adjusting-nut, g', by means of which the end of said rod can be raised or lowered and held secured at any 65 desired position in said slot to alter or vary the amount of the lateral vibration of the needle to increase or decrease the length of the lateral stitch. The other end of said bar G is slotted at g', and is secured to a slide, H, 70 by attaching said slotted end g' onto the screw h. Said slide H dovetails into a bracket, I, fastened to the arm A' of the machine by screws i i. Said bracket is provided with a pin, i', and is slotted at i', as is also the arm 75 A' at a, for the passage of a stud, h', attached to or formed on the slide H. Said stud is constructed with an opening for the reception of the shank k of a guide-pin, K, which is formed with a shoulder, k', and a head, k'', made of a 80 double-wedge or oval shape, having a thick central part, k'', and pointed ends k' k''. The head k'' of said guide-pin K projects beyond the inner wall of the arm A' and enters one of the two grooves l l' formed on the face of 85 the cam-cylinder L, secured to the shaft B. Said grooves are plain straight grooves running round said pulley for about three-quarters of its periphery, when they then cross or intersect each other, as shown in Figs. 2 and 90 3, thereby forming cam-grooves l' l'', uniting the grooves l l', which have the effect, as the cylinder L revolves, of guiding the head k'' of the pin K from one straight groove to the other, thereby moving said head from side to 95 side and reciprocating the slide H the length of the distance that the grooves are apart.

It will be seen that the lever E and its appliances may be attached to the needle-bar C of an ordinary sewing-machine with but little 100

alteration of said needle-bar; that the lever F may be secured to the head of the machine by simply drilling a hole to receive the pivot f'; that the cam-cylinder L may be bolted directly 5 on the driving-shaft, and the bracket I applied after cutting the slot a in the arm. The devices are thus constructed for ready attachment to machines of a certain common construction without any radical change or alteration 10 other than an ordinary mechanic can make in a short time at little expense.

The operation is substantially as follows: All of said parts being attached to a sewing-machine, as shown, the shaft B being revolved, 15 the needle-bar C and needle-carrying lever E are reciprocated vertically, the post E' moving up and down in the bifurcated end of the lever F. On the ascent of the needle the head K² of the guide-pin K passes through one of 20 the straight grooves l l' until the needle has nearly completed its ascent; but before doing so said head k² enters one of the cam-grooves l' l'', and is thereby moved from side to side, passing out of groove l into the groove l', or 25 vice versa, thereby reciprocating the slide H and moving the rod G forward or backward, oscillating the lever F either to the right or to the left, as shown in dotted lines 1 1, Fig. 1. As said lever F oscillates the bifurcated end 30 f moves the guide-post E' from side to side, thereby vibrating the needle-carrying lever E on its pivotal connection (to reciprocate the needle c to make a lateral stitch) in the direction shown in dotted lines 2 2 of Fig. 1. The 35 needle then descends in a different plane from that in which it ascended. When the needle again ascends the head k² is reversely moved by the grooved cylinder, thereby reversing the movement of the slide H, rod G, lever F, post E', and needle-carrying lever E, to move the 40 needle back to the first-described position or plane, and the lateral stitch is completed. The movements of said parts are so timed that the head k² will not be reciprocated until the needle 45 has nearly completed its ascent, when the lower part of the guide-post E' is then well up within the forks of the lever F, at which position said post can be more steadily and easily moved to vibrate the needle-carrying arm E 50 without straining the same.

To vary the length of the stitch the end of the rod G is moved up or down in the slot f''. To shorten the stitch the end of the rod is raised to the upper part of said slot; if depressed toward the lower part of the slot, the 55 stitch is lengthened.

If at any time the attachment is not desired to be used, by lifting and removing the slotted end g³ from the screw h and securing it on the 60 pin i² of the bracket I, as shown by dotted lines, Fig. 1, the rod G will be disengaged from the slide H, and the needle will then be vertically reciprocated only, as in the ordinary sewing-machine, the needle being held fixedly 65 in position for that purpose by reason of the slotted end g³ of the bar G being immovably secured to the stationary pin i². By unscrew-

ing the thumb-screw g² and slipping the rear end of the rod G off of the screw h and turning the section G' of said rod to the right or left, 70 said sections G' G² are adjusted to increase or decrease the length of the rod G, which, when again connected to the lever F, has the effect of altering the angle of inclination of the same without necessarily varying the length of the 75 stitch. Said variation in its inclination is communicated to the post E', thence to the needle-carrying lever E, and the needle is thereby shifted so that it will sew close up to the edges 80 of the button-hole or fabric to be overseamed. Thus, for instance, if the parts of the attachment are so adjusted that the needle has been making a stitch of the length shown at 1 1, Fig. 8, and the rod G is adjusted in the slot f'' to increase the length of said stitch to the size 85 indicated by line 2 2 in said figure, this increase would be equally distributed on both sides of the center of the length of said stitch or of the center of vibration of the needle, and the latter would make one of its descents in 90 the middle of the opening of the button-hole, as shown, thereby forming a much larger thread-loop than is required to bind the edge of the 95 button-hole.

If, now, the rod G be shortened, as described, 95 the upper end of the lever F will by such action be slightly moved toward the rear of the machine, varying its angle of inclination and moving the guide-post E' to shift the needle-carrying lever E, thereby moving the 100 needle toward the edge of the button-hole, so that it will reciprocate in one of its vertical planes adjacent to the said edge, as indicated by lines 3 3 of Fig. 8, thereby avoiding the unnecessary length of thread-loop to bind said 105 edges and obtaining a greater hold upon the cloth. If, however, the length of the stitch is varied so as to be less than that shown by lines 1 1, Fig. 8, the needle would then pierce the cloth in both of its descents; hence the 110 rod G must in such cases be lengthened, thereby moving the upper end of the lever F outward to alter the angle of inclination of said 115 lever to the reverse of that already described, so as to shift the needle toward the edge of the 120 button-hole, as indicated by line 4 4, Fig. 8.

By altering the length of the rod the stitch may be thrown to either edge of the button-hole without dismembering the machine.

If desired, two or more needles may be employed, as shown in Fig. 5.

I do not limit myself to the described mode of carrying the needle, as any other may be used. For instance, the needle-bar may be reciprocated back and forth as well as vertically.

I am aware that with a needle having invariable horizontal and vertical reciprocating movements a supplemental needle has been combined, and that devices have been used for 130 adjusting the supplemental needle to and from the first; but it will be apparent that in such case the width of the stitches cannot be varied, and that the working position of the needle,

deriving its movements from the horizontal reciprocating devices, cannot be altered.

I claim—

The combination, in an overseaming-machine, of a shuttle, a fixed race, a needle, devices for reciprocating the needle vertically and horizontally, appliances, substantially as described and shown, whereby the horizontal working position of the needle may be altered, and devices whereby the extent of its hori-

zontal reciprocation may be varied, substantially as and for the purpose set forth.

In testimony whereof I have signed my name to this specification in the presence of two subscribing witnesses.

WM. M. SMITH.
